WITNESS

H. Kowalewski

Louis Steinberger, INVENTOR
BY
Cornelia C. Billings
his ATTORNEY

UNITED STATES PATENT OFFICE.

LOUIS STEINBERGER, OF BROOKLYN, NEW YORK.

STRAIN INSULATOR.

Application filed November 30, 1918. Serial No. 264,772.

To all whom it may concern:

Be it known that I, LOUIS STEINBERGER, a citizen of the United States, and a resident of the borough of Brooklyn, city and State 5 of New York, have invented certain new and useful Improvements in Strain Insulators, of which the following is a specification.

One of the objects of my invention is to 10 provide a strain member for an insulator in which the exposed bridge portions are insulated from the leg portions.

Another object of my invention is to insulate the strain members from each other 15 by means separate and independent of the main insulator body.

Another object of my invention is to so 20 construct a strain insulator that it may be readily assembled and disassembled, and to provide means for insulating the parts of 25 the strain members from each other by means which are separate from and independent of the main body of the insulating material.

Another object of my invention is to provide a removable sheath or cover of insulating material for the leg portion of the strain members of an insulator.

Referring to the drawings in which the 30 same reference character indicates the same part in the several views:

Fig. 1 is a view partly in elevation, partly in vertical section, of an insulator embodying my invention.

Fig. 2 is a section on line 2—2 of Fig. 1.

Fig. 3 is a detail.

In constructing my invention I form the body of insulating material A into suitable shape, preferably that shown in the drawings, in which the body is elongated and has an alternate series of horizontal grooves *a* and ridges *b* in the surface thereof thereby extending the area of the same, and at each end I provide a projecting portion 10 and 45 11, each of which portions is covered with a metal cap C and C' for resisting the crushing action of the strain members.

The body portion of the insulator is made of any suitable insulating material, such as that well known in the art as electrose, or may be made of porcelain, glass or any other suitable heat resisting or fireproof insulating material.

When the body is made of electrose it may 50 be molded into the form shown, and the metal caps or strain resisting members C

and C' are preferably molded onto the respective ends of the body of insulating material, or they may be cemented thereto or threaded thereon, as illustrated at 40 in Fig. 60 1, whereas when the body of insulating material is made of glass, porcelain or other suitable fire-proof or vitreous material, the metal caps C and C' are secured to the insulator by cement, or they may be screw 65 threaded as also illustrated at 40 in Fig. 1.

The caps C and C' may be of any other suitable shape or form than that illustrated.

The insulator body at each end is lessened in diameter as shown, thereby forming 70 ridges or seats 15 and 16 for the reception of the rings 17 and 18 forming a part of the bridge portions of the strain members.

The strain members are duplicates of each other and a description of one serves for all, 75 it being understood that the two strain members are secured to the insulator body in positions at right angles to each other as clearly shown to prevent them from moving towards each other when subject to strain. 80 This may be accomplished in many ways; one way is to provide grooves or seats 60 for engagement with the radially extending arms 20, 21, 20' and 21' as shown. The arms 20, 21, 20' and 21' are connected respectively with the leg portions 22, 23, 24 and 25 of the strain members. The upper ends of the strain members are screw-threaded and nuts 30 and 31 engage with the said screw threads and with the screw threads on 90 the removable portion 50 of the strain member as shown.

Tubes T, T', T² and T³ of the insulating material are respectively placed around the entire leg portions of the strain members 95 and each extends from the radial projecting arms 20, 21, and 20', 21' to the nuts 30 and 31 and are held in position between the two, the nuts preventing the tubes from moving up or down or making any change in position. It is to be understood that the same construction and arrangement is present 100 with respect to the other strain members.

The position of the securing nuts should be at least four times the distance of the ring shaped bridge members from the insulator tube in order to secure an effective insulation.

As will be seen from the structure above described, the body of insulating material and the strain members may be assembled 110 readily and quickly.

The purpose of the insulating tube around

the legs of the strain members is to increase the insulation value of the insulator. Without the tube, the limit of insulation value of this insulator would be the air space α between the arm or leg and the strain member and the ring of the bridge portion. By encasing the legs of the strain members by means of the sleeve or tube of insulating material I have increased the value of the insulation by substituting for a portion of the air insulation an insulating material that resists being punctured very much more than air does.

As changes of construction could be made within the scope of my invention, it is intended that all matter contained in the above description or shown in the accompanying drawings shall be interpreted as illustrative and not in a limiting sense.

Having now described my invention, what I claim as new and desire to secure by Letters Patent is:

1. In a device of the kind described, an insulator consisting of an insulating body and exposed strain members removably secured thereto, the leg portions of which are situated at a distance therefrom, said strain members being insulated from each other by means other than air and the main insulating body.

2. In a device of the kind described, an insulating body, strain members provided with bridge and leg portions, the bridge portions engaging the insulating body and the leg portions of the strain members being spaced from said insulating body and encased in individual sleeves of insulating material.

3. In a device of the kind described, an insulating body, strain members provided with bridge and leg portions, the bridge portions engaging the insulating body and the leg portions of the strain members being situated at a distance from the insulating body, and a tube or sleeve of insulating material surrounding each of the legs of the strain members.

4. In a device of the kind described, a body of insulating material, strain members provided with bridge and leg portions removably secured thereto, and a sleeve or jacket of insulating material removably secured to each of the leg portions of the strain members.

5. In a device of the kind described, a body of insulating material, strain members having bridge portions contacting with the ends of said body, leg portions extending axially beyond said bridge portions, the leg portions of each strain member being insulated from the bridge portion of the other strain member by tubular insulators surrounding the said leg portions.

6. In a device of the kind described, a body of insulating material, strain members having bridge portions contacting with the ends of said body, leg portions extending axially beyond said bridge portions, the leg portions of each strain member being insulated from the bridge portion of the other strain member by tubular insulators surrounding the said leg portions, and extending on said leg portions past said bridge portions.

7. In a device of the kind described, a body of insulating material, strain members having bridge portions contacting with the ends of said body, leg portions extending axially beyond said bridge portions, the leg portions of each strain member being insulated from the bridge portion of the other strain member by tubular insulators surrounding the said leg portions, yokes for said leg portions, and nuts attaching said yokes to said leg portions and holding the insulating tubes in position on said leg portions.

In witness whereof, I have hereunto set my hand at the borough of Manhattan, city and State of New York, this 19th day of November, 1918.

LOUIS STEINBERGER.
In presence of—
ZITA M. GRAHAM.
